UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

GUN.

1,240,991.

Specification of Letters Patent. Patented Sept. 25, 1917.

Application filed October 4, 1916. Serial No. 123,644.

To all whom it may concern:

Be it known that I, CHARLES F. LEFEVER, a citizen of the United States of America, residing at Plymouth, in the county of Wayne and State of Michigan, have invented certain new and useful Improvements in Guns, of which the following is a specification, reference being had therein to the accompanying drawings.

10 The invention relates to guns of the type adapted for the shooting of a cork or other light projectile by the impact of compressed air. It is one of the objects of the invention to obtain a construction that closely 15 simulates a real gun, and further to obtain a simple and inexpensive construction to manufacture. To this end the invention comprises various features of construction as hereinafter set forth.

20 In the drawings:

Figure 1 is an elevation of the gun;

Fig. 2 is a longitudinal section.

Fig. 3 is a section on line $x-x$ Fig. 2.

A is the stock of the gun, and B the bar-

25 rel preferably formed of a sheet-metal blank fashioned to form a frame portion C and cylindrical barrel portion D. E is a piston abutment, F the piston, G the piston shank, H the spring and I the spring abutment.

30 In order to give the appearance of a real gun and also to provide a loading mechanism that is easily operated, a pump lever spring compressing mechanism is provided. This comprises a handle J, which is slidable 35 upon the barrel, preferably by engaging the seam K which unites the edges of the blank. L and M are two links of a toggle lever, the former being pivotally attached at N to the handle J and the latter being fulcrumed

40 upon a pin O passing through the frame. The link M is connected to the shank G of the piston or plunger in such a manner that the bowing of the toggle will retract the piston and compress the spring. It is, how- 45 ever, difficult to arrange such an operating mechanism within the space limits of the comparatively short length barrel, and I have therefore devised a specific construction for accomplishing this, as follows:

50 The links L and M are formed of sheet-metal bent into a U-shaped cross section. P is a link embraced by the sides of the link M and pivotally attached thereto at a point intermediate its fulcrum O and the pivotal connection M' with the link L. The link P

may also be formed of sheet-metal bent into U-shaped cross section, and its inner end embraces the shank G of the plunger, to which it is attached by a cross pin Q passing through a slot Q' in said shank. The shank 60 G is formed of a sheet-metal strip, which in addition to the slot Q' is provided with a slot G' for engaging the fulcrum pin O. The slot Q' is also of sufficient length to engage cross pin I and to permit of longitudinal movement of the shank when the plunger is retracted. Thus the pins I and O form guides for the shank G. At its inner end the plunger G is bent at an angle, as indicated at S, which forms a shoulder 70 for engagement with the sear. The sear is integral with the trigger T, which is so fashioned as to simulate a trigger guard, projecting downward through a slot in the frame. U is a fulcrum pin for the trigger 75 and V is a hook or shoulder which constitutes a sear.

In operation, when the handle J is drawn rearward, the toggle lever links L and M will break downward, assuming the angular 80 position shown in Fig. 2. This movement will draw upon the link P, which in turn through the pin Q will draw upon the shank G, pulling the latter rearward until the shoulder S engages the sear V. The handle 85 J may then be moved upward, straightening the toggle links L and M and also folding the link P. This movement is permitted by reason of the slot Q', which allows the pin Q to move forward when the shoulder S 90 is in engagement with the sear. To fire the gun the trigger T is operated, which depresses the sear, disengaging it from the shoulder S and permitting the tension of the spring H to drive the plunger forward until 95 it strikes the abutment E. This will compress the air within the barrel to eject the cork.

What I claim as my invention is:—

1. In a gun, the combination of a barrel, 100 a plunger therein, a spring for actuating said plunger, an abutment for said plunger and spring, a shank for said plunger extending rearward therefrom and having shoulders for engagement with the sear, a pump handle slidable parallel to said barrel, a toggle lever connected to said pump handle and fulcrumed to said barrel, the fulcrum pin passing through a slot in said shank, and a link connecting said toggle 105 110

with said shank at a point intermediate the ends of the toggle.

2. In a gun, the combination of a barrel, a plunger therein, a spring for actuating said plunger, an abutment for said spring, a plunger shank around which said spring is sleeved provided with a slot through which said spring abutment passes, the rear end of said shank being adapted for engagement with the sear, a toggle lever for retracting said plunger, having its fulcrum pin extending through a slot in said shank, and a link connected to said toggle pivotally attached to said plunger shank at a point intermediate the ends of the toggle.

3. In a gun, the combination of a barrel, a plunger therein, a spring for actuating said plunger, an abutment for said spring, a shank for said plunger, around which said

20 spring is sleeved, said shank having a slot through which said spring abutment extends and being fashioned at its rear end for engagement with the sear, and a toggle lever for retracting said plunger having its rear 25 end fulcrumed on a pin passing through a slot in said shank, a link for connecting said toggle to said shank having its point of attachment to the latter intermediate the ends of the toggle and engaging a slotted bearing, said slotted bearing permitting of the straightening of the toggle when said shank is in engagement with the sear.

4. In a gun, the combination with a barrel, of a plunger therein, a spring for actuating said plunger, an abutment for said spring, including an anchoring pin extending across said barrel, a toggle lever, a pin

40 forming a fulcrum for the inner end of said toggle, also extending across said barrel, a trigger and sear, and a shank for said plunger slotted for engagement with said anchoring pin and fulcrum pin, and a link connecting said toggle with said shank, being attached to the latter at a point intermediate the ends of the toggle and engaging 45 a slotted bearing, for the purpose described.

5. In a gun, a combined trigger and sear, comprising a stamping simulating a trigger guard and having a shoulder thereon constituting the sear.

6. In a gun, the combination with a slotted frame, of a combined trigger and sear pivotally connected to said slotted frame and having a portion projecting downward therefrom, simulating a trigger 55 guard, the concealed portion of said member being shouldered to form a sear.

7. In a gun, the combination with a barrel, of a plunger, a plunger shank formed of a metal strip longitudinally slotted and 60 having a turned flange or shoulder at its rear end, a sear for engagement with said turned flange or shoulder, and a toggle lever for retracting said plunger shank, the inner end of said toggle being fulcrumed on a 65 pin passing through a slot in said shank, a handle for actuating the opposite end of said toggle, and a link extending from said toggle to said shank, being attached to the latter at a point intermediate the ends of 70 the toggle, for the purpose described.

In testimony whereof I affix my signature.

CHARLES F. LEFEVER.
